UNITED STATES PATENT OFFICE.

WILLIAM A. MACK, OF CLEVELAND, OHIO, ASSIGNOR TO THE STANDARD SEWING MACHINE COMPANY, OF CLEVELAND, OHIO, A CORPORATION OF OHIO.

BOBBIN-CASE LATCH FOR SEWING-MACHINES.

1,053,736.

Specification of Letters Patent. Patented Feb. 18, 1913.

Application filed April 25, 1911. Serial No. 623,272.

To all whom it may concern:

Be it known that I, WILLIAM A. MACK, citizen of the United States, and resident of Cleveland, in the county of Cuyahoga and State of Ohio, have invented certain new and useful Improvements in Bobbin-Case Latches for Sewing-Machines, of which the following is a specification.

My invention relates to bobbin-case latches for sewing machines, and has for its object to provide an improved latch device of this character that will be simple in construction, efficient in operation, and capable of all necessary adjustments to adapt it for proper coöperation with the bobbin-case.

To this end the invention consists in the novel construction, arrangement and combinations of parts hereinafter set forth in detail and particularly pointed out in the appended claims.

Referring now to the accompanying drawings forming part of this specification,—Figure 1 is an enlarged assembly view, showing in side elevation the loop-taker, bobbin-case, bobbin-case latch, and their associated parts; the latch being shown in open position and the bobbin-case being shown removed from its operative position within the loop-taker and resting upon said latch. Fig. 2 is a bottom plan view, on a smaller scale, of the structure shown in Fig. 1, but with the latch in closed position and the bobbin-case held thereby in its operative position within the loop-taker. Fig. 3 is a front end elevation of the same.

Similar reference characters indicate like parts in the several figures of the drawings:

The looper mechanism in connection with which I have illustrated my invention is the same as that disclosed in Letters Patent #1,005,250, granted to me Oct. 16, 1911, and comprises a rotary loop-taker 2 mounted on the front end of a driving shaft 3 which is journaled in a frame or hanger 4 at the under side of the bed-plate 5. The loop-taker 2 is of substantially usual construction, the same being in the form of a cup-shaped disk to provide an open chamber in its face side for the bobbin and bobbin-case.

The bobbin-case, indicated at 6, is adapted to be removably retained in operative position within the open chamber of the loop-taker by means of a latch 7. This latch is here shown in the form of a plate for en-

gagement with the bobbin-case at its face side, and having two ears 8, 8, at its lower side pivoted to a supporting frame or block 9 by pivot screws 10, 10, to permit the latch being swung outwardly from the face of the loop-taker for the insertion or removal of the bobbin and bobbin-case to and from their position within the loop-taker. When the latch is swung to closed position subsequent to the insertion of the bobbin and bobbin-case into their position within the loop-taker, it is held in such position by a catch device, here shown in the form of a lever 11 pivoted to the frame 9 at 12 and having a latch-engaging shoulder 13 which is movably held in latch-engaging position by means of a spring 14 seated in a pocket of the frame 9 and pressing upwardly against the rear end of the lever, as clearly shown in Fig. 1. This catch device 11 is extended at its forward end sufficiently far beyond the coöoperating parts to permit of its being conveniently grasped by the operator when it is desired to release the bobbin-case latch 7. When the latter is released by the raising of the catch 11 from holding engagement therewith, it is automatically thrown to its open position by means of a spring-pressed pin 15 seated in the frame 9 and acting with an outward pressure against said latch. When the latch 7 is thus thrown to open position, the bobbin and bobbin-case being released thereby will also ordinarily drop outwardly from their position within the loop-taker to a position resting upon said latch, as shown in Fig. 1, where they may be conveniently reached by the operator. Subsequently and after a newly-wound bobbin has been placed in the bobbin-case, the latter will be again placed or otherwise located on the latch and the latch then swung to its closed position, which will operate to place the bobbin and bobbin-case in their operative position within the loop-taker. When the latch 7 is thus swung to closed position it will operate by contact of its upper edge with the catch 11 to raise the latter and permit of the passage of the latch 7 beneath the shoulder 13 thereon, following which said catch 11 will be caused to automatically snap into locking engagement with the latch 7 under the action of the spring 14. A finger 16 at the upper edge of the latch 7 loosely engages the bobbin-case within a recess 17

therein and thereby acts to hold the bobbin-case against rotary movement in its seat in the loop-taker.

The supporting frame 9 for the bobbin-case latch and certain of its coöperating parts as described, is here shown as being supported by means of two horizontally-arranged pins 18, 18, projecting from the front side of the shaft frame or hanger 4 and entering corresponding openings 19, 19, in the latch frame, whereby the latter may be slidingly adjusted on said pins to adjust the position of the latch relatively to the loop-taker and bobbin-case in order to provide the proper thread clearance between the latch and the face of the bobbin-case. Set screws 20, 20, carried in the latch frame for engagement with the pins 18, 18, and adjustable stop or positioning pins 21, 21, carried 20 in the frame or hanger 4 for engagement with the rear side of said latch-frame, serve as a means for firmly securing the latter in adjusted position.

The frame or hanger 4 in the present case, 25 as also in my aforesaid pending application, is shown as pivotally connected to the bed-plate by pivot screws 22, 22, although for the purpose of my present invention it may

be made integral with or otherwise connected to the bed-plate.

What I claim is:

1. In a sewing machine, the combination with a rotary loop-taker and a bobbin-case, of a hanger at the under side of the bed-plate provided with a plurality of horizontally-arranged bracket pins, a frame mounted on said pins, and a bobbin-case latch mounted on said frame.

2. In a sewing machine, the combination with a rotary loop-taker and a bobbin-case, of a hanger at the under side of the bed-plate provided with a plurality of horizontally-arranged bracket pins, a frame having openings to receive said pins and being adjustably mounted on them, means for securing the frame in adjusted position on said pins and a bobbin-case latch mounted on said frame.

Signed at Cleveland, in the county of Cuyahoga, and State of Ohio, this 4th day of April A. D. 1911.

WILLIAM A. MACK.
